UNITED STATES PATENT OFFICE.

WHEELER H. VIBBER, OF NEW LONDON, CONNECTICUT, ASSIGNOR OF ONE-HALF TO
THE GILLETTE-VIBBER CO., OF NEW LONDON, CONNECTICUT, A CORPORATION.

TERMINAL GROUND-CLAMP.

1,281,770.

Specification of Letters Patent. Patented June 14, 1921.

Application filed August 9, 1920. Serial No. 402,262.

To all whom it may concern:

Be it known that I, WHEELER H. VIBBER, a citizen of the United States, residing at New London, in the county of New London and State of Connecticut, have invented a new and useful Improvement in Terminal Ground-Clamps; and I do hereby declare the following, when taken in connection with the accompanying drawings and the characters of reference marked thereon, to be a full, clear, and exact description of the same, and which said drawings constitute part of this application, and represent, in—

Figure 1, a view in elevation showing my improved terminal or ground clamp, applied to a grounded pipe and having an electric conductor or wire inserted into it, the pipe and wire being shown in transverse section.

Fig. 2, a plan view of the clamp as supplied to the trade.

Fig. 3, an edge view thereof.

My invention relates to an improved terminal or ground clamp for electric conductors, the object being to produce at a low cost for manufacture, a simple convenient and effective clamp of the character described.

With these ends in view my invention consists in a terminal or ground clamp having certain details of construction as will be hereinafter described and pointed out in the claims.

As herein shown my improved clamp consists of a flexible metal strip 2 of uniform width, one end being furnished with a series of perforations 3 to adapt the clamp to be applied to grounding pipes varying in diameter, a standard pipe being shown at 4 in Fig. 1. The opposite end of the strip is bent to form an inverted loop 5 of which the legs 6 and 7 are perforated as at 8 and 9 for the reception of a clamping screw 10 furnished with a nut 11 which is screwed up against the outer face of the opposite end of the strip 2, the intermediate portion of which is carried around the pipe and im-

posed, as it were, upon the outer face of the outer leg 7. The outer leg 7 is itself bent as at 12 near the bow of the loop to 50 form a conductor-receiving eye 13, thus giving the lower end of the leg 7 an outward flare (Fig. 3) so as to increase its spring action and hence its ability to contract the eye 13 and grip the same upon the wire 14 when 55 the device is applied as shown in Fig. 1.

I claim:

1. In a terminal or ground clamp, the combination with a flexible metal strip formed at one end with perforations and 60 having its opposite end bent to form an upstanding U-shaped loop the legs of which are formed with aligned perforations, of a clamping screw which passes through the said perforations in the legs of the loop 65 and through one of the perforations in the other end of the strip, and a nut positioned on the screw to engage with the outer face of said other end of the strip, whereby a conductor or wire inserted into the bow of the 70 loop is gripped and held when the loop is contracted by the action of the clamping screw.

2. A terminal or ground clamp for electric conductors consisting of a flexible metal 75 strip formed at one end with a plurality of perforations and bent at its other end to form an upstanding loop the legs of which are perforated and the outer or free leg of which is bent outwardly near the bow 80 of the loop, in combination with a screw passing through the said perforations in the legs of the loop and through one of the perforations in the other end of the strip, and a nut positioned upon the screw to engage 85 with the outer face of said other end of the strip.

In testimony whereof, I have signed this specification in the presence of two subscribing witnesses.

WHEELER H. VIBBER.

Witnesses:

LINDA YARVOTS,
R. K. BURROWS.
